Primary Examiner — Catherine S Posthauer

(74) Attorney, Agent, or Firm — Dorsey & Whitney LLP

(57) **CLAIM**

The ornamental design for a base plate for a can as shown and described.

DESCRIPTION

1.1 : Exterior-side-up (bottom) perspective view

1.2 : Interior-side-up (top) perspective view

1.3 : Front

1.4 : Exterior-side-up (bottom) view

1.5 : Interior-side-up (top) view

2.1 : Exterior-side-up (bottom) perspective view

2.2 : Interior-side-up (top) perspective view

2.3 : Front

2.4 : Exterior-side-up (bottom) view

2.5 : Interior-side-up (top) view

3.1 : Exterior-side-up (bottom) perspective view

3.2 : Interior-side-up (top) perspective view

3.3 : Front

3.4 : Exterior-side-up (bottom) view

3.5 : Interior-side-up (top) view

The front view, back view, left side view and right side view in the reproductions are identical; the broken lines in the reproductions show portions of each product that form no part of the claimed design; the shadings in the reproductions represent contours only and do not illustrate an ornamentation or decoration on the surface of the product.

1 Claim, 15 Drawing Sheets
